UNITED STATES PATENT OFFICE.

CHARLES Z. SMITH, OF ALBANY, NEW YORK, ASSIGNOR TO MOTOR IGNITION CORPORATION, OF ALBANY, NEW YORK, A CORPORATION OF NEW YORK.

IGNITION SYSTEM.

Continuation of application Serial No. 429,845, filed December 11, 1920. This application filed May 4, 1922. Serial No. 558,385.

To all whom it may concern:

Be it known that I, CHARLES Z. SMITH, a citizen of the United States, a resident of Albany, in the county of Albany and State 5 of New York, have invented a certain new and useful Improvement in Ignition Systems, of which the following is a specification.

The invention has for an object to provide 10 an ignition system in the operation of which the voltage of the secondary circuit will rise to a proper value notwithstanding carbonization or other defects in the spark plug tending to short circuit the secondary circuit, and further to bring about 15 the above result in such manner as to avoid an excessive voltage or other derangement in the secondary circuit when the spark plug is functioning properly.

Another object is to intensify the spark obtainable with the secondary circuit of an ignition system.

A further object is to accomplish either or both of the above results without giving rise to substantial absorption or loss of energy.

The invention also contemplates a simple and compact form of holder or cartridge containing devices whereby the above-mentioned 30 results may be secured, and which may readily be inserted in such a secondary circuit to afford proper electrical connections to such devices.

Further objects and advantages of the invention will be in part obvious and in part 35 specifically pointed out in the description hereinafter contained which, taken in connection with the accompanying drawings, discloses a preferred embodiment of the invention; such embodiment, however, is to be considered merely as illustrative of its principle. In the drawings:

Fig. 1 shows diagrammatically a portion of an ignition system adapted to operate 40 according to the invention.

Fig. 2 is an end view of a holder or cartridge containing certain devices which are included in the circuit shown in Fig. 1.

Fig. 3 is a central longitudinal section of 50 the holder or cartridge shown in Fig. 2.

If the secondary circuit of an ignition system be of such character that carbonization or other defects in the spark plug can result

in a (high resistance) short circuit of such secondary circuit, under such conditions the 55 voltage of the secondary coil will fail to build up to a proper value, and the result will be abnormally heavy flow of current in the primary circuit, thus causing arcing, 60 pitting and wearing away of the primary 65 contacts.

On the other hand, if a rise in voltage in the secondary circuit be insured under 70 all conditions by the use of a plain series gap in connection with a spark plug, the 75 voltage of the secondary circuit may rise to such a high value as to run the risk of puncturing the secondary insulation, when the spark plug is functioning properly.

It is, therefore, the object of the present 75 invention to secure a proper rise in voltage in the secondary coil, and substantially normal current therein, when the resistance of the spark plug falls below normal, and yet to avoid excessive secondary voltage when 80 the spark plug is functioning properly which might lead to injury to the secondary insulation.

Referring to Fig. 1 of the drawings, I 85 have shown, more or less conventionally, certain portions of an ignition system, including a secondary coil 1, which is to be considered merely as any suitable medium for supplying electrical energy through conductors 2 and 3 to the usual spark plug 4 85 of a gas engine or the like.

In order to bring about a proper voltage in the secondary circuit, both when the spark plug 4 is functioning properly and when it has been carbonized or otherwise 90 fouled, I interpose between one side of the coil 1 and one electrode of the spark plug 4 an oscillating circuit comprising a condenser or capacity 5 and an additional gap 6, made up of electrodes 7 and 8, the condenser 5 95 and gap 6 being in parallel with each other and both in series with spark plug 4. Thus, when spark plug 4 is functioning properly, the potential of coil 1 will initially be impressed upon the electrodes of the spark plug through condenser 5 until such potential is built up to a value sufficient to bridge the electrodes of the spark gap. The collapse 100 of the electrostatic field in condenser 5 will then cause the condenser to discharge 105 through the oscillating circuit comprising

- condenser 5 and the additional gap 6, with the result that gap 6 will be rendered conductive, whereby the current from coil 1 may flow through conductor 2, gap 6, across spark plug 4 and conductor 3 without substantial diminution being caused by the gap 6, since the resistance of the latter has been substantially minimized by means of the discharge from condenser 5.
- 10 I prefer to employ a condenser 5 of very small capacity, for example, in the order of .001 mfd., for ignition circuits of ordinary character, in order that the amount of energy absorbed in the condenser in its discharge across the additional gap 6 may be relatively small. Thus, the energy which may be obtained in the discharge across the electrodes of spark gap 4 will not be materially decreased.
- 15 20 I prefer to include in the oscillating circuit, comprising the condenser 5 and the additional gap 6, an inductance which, in the present embodiment, is in the form of two coils 9 and 10, respectively, which are in series with condenser 5. The inductive effect of these coils is preferably so related to the capacity of condenser 5 that sustained oscillations are set up across gap 6 through the condenser and inductances 9 and 10. In other words, the combined inductance of coils 9 and 10 in micro-henries should be about equal to the capacity of the condenser in micro-farads. Thus, a condition of resonance will obtain in the oscillating circuit and gap 6 will be maintained conductive for a prolonged period of time without substantial losses of energy, whereby the current from coil 1 may flow across this gap to the spark plug 4 sufficiently long to give proper ignition. As the condenser 5 discharges through inductances 9 and 10, the collapse of their electro-magnetic fields will set up a counter-electromotive force which charges the condenser in the opposite direction, and when the current from coil 1 reverses, the oscillating discharge across gap 6, will keep this gap conductive, and the action of a spark at plug 4, followed by a spark at the additional gap 6, will be repeated. However, it will be noted that the potential required to bridge spark gap 4 initially is not substantially greater than would be required if the oscillating circuit comprising the condenser, inductance and additional gap, were omitted, and therefore the inclusion in the circuit of the features necessary to enable it to operate in accordance with the invention does not give rise to a potential which would be high enough to strain unduly the insulation of the circuit.
- 25 Furthermore, in case the spark plug 4 should be short-circuited, by carbonization or otherwise, the voltage of the coil 1 will still build up to its normal value, since the potential of the coil will be impressed upon

condenser 5 in the first instance until such potential rises to a value sufficient to bridge the additional gap 6, and the potential at which this gap breaks down is approximately the same as is required to break down the gap at spark plug 4 when the latter is functioning properly. Thus, when spark plug 4 is fouled, no short-circuit results in the secondary, which would result in the occurrence of such heavy current in the primary circuit as to burn the primary contacts.

The invention may be readily adapted to known ignition systems by means of a structure such as is shown in Figs. 2 and 3. As appears therein, a suitable holder 11, which ordinarily will be of insulating material, is provided with terminals 12 and 13 at its opposite ends, the terminal 12 being illustrated as provided with a binding-nut 14, while terminal 13 holds in position a connector-clip 15, as by means of a nut 16. If a clip, such as the member 15, be employed, the holder and the parts contained therein may be readily mounted upon the spark plug, or any other convenient element which forms a part of the secondary circuit, the terminal 12 then being connected to one of the conductors 2 or 3 of Fig. 1.

In the present instance, metal caps 17 and 18 are pressed over the ends of the insulating holder 11, and terminals 12 and 13 are in the form of screws passing through the caps and clamped thereto by the nuts 19 and 16, respectively. The caps 17 and 18 are sealed in position to provide fluid-tight joints, so as to avoid short circuiting of the parts carried within the holder, due to entrance or oil or the like.

The condenser 5 is contained within the holder 1, and in the present instance is also of cylindrical shape and substantially coaxial with holder 11, such condenser consisting of the dielectric 20, of glass or the like, and the inner and outer coatings 21 and 22, respectively.

The inductances 9 and 10 are disposed, respectively, between the opposite end surfaces of the condenser and the ends of holder 11, such inductances preferably consisting of coils of resilient wire which are compressed between the caps 17 and 18 and conducting discs 23 and 24, respectively, on the ends of the condenser, whereby the coils serve to hold the condenser yieldingly in position as well as to lead current thereto from terminals 12 and 13, respectively.

The electrodes 7 and 8 of additional gap 6 are also contained within holder 1, and in the present embodiment are in the form of angularly-shaped plates having feet 25 and 26 adapted to be clamped under the heads of terminals 12 and 13 and lying along condenser 5 with their ends spaced to provide the additional gap 6 at the intermediate portion of the holder. An insulating sleeve 29

may be interposed between the condenser and the electrodes 7 and 8 to prevent short-circuiting.

I also prefer to provide an opening 27 in 5 the portion of holder 11 which overlies the gap 6, so that the action of the spark across the gap may be observed, a transparent mica window 28 being hermetically sealed over the opening 27 to eliminate the danger of an 10 exposed spark.

Ordinarily, when the spark plug 4 is working properly, a strong spark of reddish-white color will be observed through opening 27, while if the plug is fouled, the spark 15 appears weaker and is of a bluish tinge.

This application contains subject matter common to my co-pending application, Serial No. 429,845, filed December 11, 1920, entitled "Ignition system."

20 While the specific embodiment of the invention has been described, it is obvious that many changes may be made therein without departing from its principle, as defined in the following claims:

25 I claim:

1. An ignition system comprising a secondary circuit having a secondary coil, a spark gap, and means for initially impressing the potential of said circuit upon said 30 spark gap, and means associated with said secondary circuit for effecting a rise in voltage of said secondary coil to substantially normal voltage in case the resistance of said spark gap is below normal, said means being 35 operative to bring about only a substantially normal rise in voltage of the secondary coil when said spark gap is functioning properly.

2. An ignition system comprising a secondary circuit having a secondary coil, a spark gap, and means for initially impressing the potential of said circuit upon said spark gap, and means associated with such secondary circuit for effecting a rise in voltage in the secondary circuit when the voltage required to bridge said spark gap is below normal, commensurate with the rise in voltage when said spark gap is functioning properly.

30 3. The combination with an ignition system comprising a secondary circuit having a secondary coil, and a spark gap, of an additional spark gap associated with said secondary circuit, means for initially impressing the potential of said circuit upon said spark gap, and means associated with such additional spark gap whereby, when the first-mentioned gap is short-circuited the voltage of said secondary coil will build up 45 to a voltage commensurate with the rise in voltage when said first-mentioned spark gap is functioning properly, (and said additional spark gap will be subjected to such voltage.

4. An ignition system comprising a sec-

ondary circuit having a secondary coil, a spark gap, and means for initially impressing the potential of said circuit upon said spark gap, and means associated with said secondary circuit for effecting a rise in voltage in the secondary circuit, when the voltage required to bridge said spark gap is below normal, commensurate with the rise in voltage when said spark gap is functioning properly, said means comprising a condenser in the secondary circuit and an additional spark gap in parallel with said condenser. 75

5. The combination, with secondary circuit of an ignition system containing a secondary coil and a spark gap, of an oscillating circuit interposed between one side of the coil and one electrode of the spark gap, said oscillating circuit comprising a condenser and an additional gap in parallel 80 and also including an inductance.

6. In combination, a secondary circuit with an ignition system containing a secondary coil and a spark gap of an oscillating circuit interposed between one side of the coil and one electrode of the spark gap, said oscillating circuit comprising a condenser and an additional gap in parallel and also including an inductance, the values of inductance and capacity being chosen to produce substantial resonance, whereby sustained oscillations are produced in the additional gap across which the current from the secondary coil may flow to the spark gap. 90

7. In combination, a hollow holder having terminal connections thereon, a condenser and an inductance coil contained therewithin, said condenser being substantially coaxial with said coil, and electrodes also within said holder lying along said condenser and coil to make up a spark gap. 105

8. In combination, a hollow holder having terminal connections thereon, a condenser and an inductance coil contained therewithin, said condenser being substantially coaxial with said coil, electrodes also within said holder lying along said condenser and coil to make a spark gap, and means for placing said spark gap in parallel with the condenser and coil. 110

9. In combination, a hollow holder having terminal connections thereon, a condenser therewithin, and means to hold condenser in proper position comprising an inductance coil, said coil bearing against a face of said condenser. 120

10. In combination, a hollow holder having terminal connections thereon, a condenser disposed within the central portion of said holder, and inductances located respectively between opposite surfaces of said condenser and the ends of said holder. 125

11. In combination, a hollow holder having terminal connections thereon, a con-

- 20 denser disposed within the central portion of said holder, and inductances located respectively between opposite surfaces of said condenser and the ends of said holder, said inductances comprising coils of resilient wire respectively bearing against the opposite surfaces of said condenser, and assisting to maintain the latter in proper position.
- 25 10 12. In combination, a hollow cylindrical holder of insulating material having terminals at its ends, a condenser disposed within the central portion of said holder, inductances located respectively between opposite surfaces of said condenser and the ends of said holder, said inductances comprising coils of resilient wire respectively interposed between the opposite surfaces of said condenser and the respective terminals,
- 30 15

35 whereby said inductances assist in maintaining the condenser in proper position and afford electrical connection thereto.

25 13. In combination, a hollow cylindrical holder having terminal connections thereon, a condenser within said holder of cylindrical form and substantially coaxial with the holder, an inductance coil interposed between said condenser and one end of the holder and electrodes interposed between the condenser and the side wall of the holder, said electrodes lying along the condenser and having their ends spaced to provide a gap at the intermediate portion of the cylinder.

30 35 In testimony that I claim the foregoing I have hereunto set my hand this 31st day of March, 1922.

CHARLES Z. SMITH.
